(57) **CLAIM**

The ornamental design for a surgical stapler end effector sled as shown and described.

DESCRIPTION

FIG. 1 is a perspective view of surgical stapler end effector sled, showing our new design;

FIG. 2 is a front elevational view of the surgical stapler end effector sled of FIG. 1;

FIG. 3 is a rear elevational view of the surgical stapler end effector sled of FIG. 1;

FIG. 4 is a right elevational view of the surgical stapler end effector sled of FIG. 1, with the left elevational view being a mirror image thereof;

FIG. 5 is a top plan view of the surgical stapler end effector sled of FIG. 1; and,

FIG. 6 is a bottom plan view of the surgical stapler end effector sled of FIG. 1.

The broken lines shown in the drawings depict portions of the surgical stapler end effector sled that form no part of the claimed design.
